UNITED STATES PATENT OFFICE.

LOUISE F. ZIES, OF BALTIMORE, MARYLAND.

NIGHTGOWN.

1,233,156.

Specification of Letters Patent. Patented July 10, 1917.

Application filed December 22, 1914. Serial No. 878,479.

To all whom it may concern:

Be it known that I, LOUISE F. ZIES, a citizen of the United States, residing at Baltimore, in the State of Maryland, have 5 invented certain new and useful Improvements in Nightgowns, of which the following is a specification.

This invention relates to improvements in night gowns, and is especially adapted for 10 use in hospitals, or persons confined to bed. The object of the invention, is to provide a gown which may be placed upon the patient or removed therefrom, without raising the body or arms and with comparatively little 15 movement of the body or arms.

The invention consists of the novel construction and arrangement of the parts and combination of parts hereinafter more fully set forth in the following specification and 20 pointed out in detail in the claim.

In the accompanying drawing,—

Figure 1 is a front view of my invention. Fig. 2 is a front perspective view of one side of the gown.

25 Referring to the accompanying drawing, forming part of this specification, and in which like reference numerals designate like parts throughout the several views thereof, 1 designates one side of the gown and 2 the other side. The side 1 is provided along its front edge with eyelets, or holes, 3 and along the edge of the back with eyelets, or holes, 4, and the piece 2 is provided with eyelets or holes 5, along its front edge, and 30 with eyelets, or holes 6 along the edge of the back. The eyelets 3 and 5 are coincident when the two back edges are fitted together and are held by a tape, or lace 7, passing therethrough, and the eyelets 4 and 6 are 35 coincident when the front edges are brought together, and are held by a tape, or lace 8, passing through said eyelets. The said tapes or laces are held in position by a knot or loop at each end and are adapted to be 40 drawn through said eyelets from either end. The sleeves 9 and 10 are open along their 45 upper edges from the neck to the ends. The front and back edges of the two sleeves 9 and

10 each being provided with eyelets 11 and 12 respectively, which coincide when the 50 said front and back edges are brought together and are held in position by the tapes or laces 13 and 14, each of which is provided with a knot or loop, at each end to prevent slipping through said eyelets and are adapted to be drawn through the said eyelets from either end. 55

When the gown is on the patient it can readily be removed by loosening the loops at the top of the laces and then drawing said 60 laces out of the eyelets. The two parts of the gown can then be removed from each side with but little or no movement of the patient's body. When the gown is placed on the patient, both sides are placed in position and laced over the arms, then by 65 slightly turning the body the back can be laced and then the front.

It will thus be seen that the gown may be placed upon the patient or removed without raising the body and with little or no movement of the patient. 70

While I have shown the two parts and the shoulders laced, it is obvious any other suitable fastening means may be employed. 75

Having thus described my invention, what I claim is:

A night gown comprising two pieces detachably connected in the center at the front and back thereof, and each piece having 80 a sleeve open at the top throughout its entire length, the overlapping edges of said sleeves being provided with eyelets, a lace for each sleeve adapted to be drawn from either end thereof, a lace for the overlapping 85 front edges adapted to be drawn from either end, and a lace for the overlapping back edges adapted to be drawn from either end thereof.

In testimony whereof I affix my signature 90 in presence of two witnesses.

LOUISE F. ZIES.
